UNITED STATES PATENT OFFICE.

GIUSEPPE MADASCHI, OF MILAN, ITALY.

APPARATUS FOR THROWING BOMBS OR TORPEDOES.

Application filed May 14, 1927, Serial No. 191,460, and in Italy May 26, 1926.

The present invention is a weapon based on new principles, having the object of throwing at a great distance, projectiles of considerable dimensions and weight, in respect of the weight, dimensions and general hardiness, of the weapon itself.

The characteristic features of the present new weapon, are embodied in the firing barrel, in the projectile and in the standard or carriage.

In the accompanying drawings is shown, as illustration of the principles hereafter disclosed, a weapon with its projectile and with its carriage, any alterations in the form or dimensions of the weapon itself or in the choice of the most convenient materials for its construction being understood to remain within the scope of present invention and appended claims.

Fig. 1 shows a section of the apparatus.
Fig. 2 shows a front view of the same.

Fig. 3 shows a view of the outside barrel.
Fig. 4 shows a cross-section, in enlarged scale, of the bottom of the bomb-thrower.

Fig. 5 shows a longitudinal section of the same.

Fig. 6 shows, to enlarged scale also, a section of the butt end illustrating how the capacity of the explosion chamber can be made to vary with the angle of fire.

Fig. 7 shows in longitudinal section a different form of execution of the main part of said apparatus with the bomb fitted to it.

Fig. 8 shows a view of the barrel of the same.

Fig. 9 shows a cross section along line 9—9 in Fig. 7.

The projectile or bomb *f* to be employed with the weapon of the present invention, is a hollow body of different shape and dimensions according to its use (see Figs. 1 and 7).

At its rear is arranged either a ring *g* containing a number of balls rollers or similar members *h* movable or fixed (Figs. 1, 4, and 5) having the object of engaging, at the start, the external rifling of the firing barrel *a* so as to follow its helical development and thus impart to the projectile a spinning action.

A long slender tube *d*, integral with the bomb, is positioned coaxially within said bomb. Said tube *d* has the rear end thereof contracted in diameter as at *i* (Fig. 1) and contains a charge of solid, liquid or gaseous explosive. This charge will hereinafter be

called the reaction charge since it acts to maintain the initial velocity imparted to the projectile by the propelling charge.

Properly inclined holes are drilled around said tube in such a way as to send the hot gases issuing at high speeds from the same tangentially against the internal special rifling *e* of the firing barrel (see Fig. 4) so as to utilize their momentum to help the spinning of the projectile.

The firing barrel *a* is a hollow cylinder, closed by a movable breech plug *b* to which can be given inside the barrel a shift proportional to the firing angle of the barrel by means of a screw geared to a sector fixed to the standard. The firing tube is surrounded by a sleeve having two trunnions *c* by which it rests on the carriage, and in the same way as with howitzers allows the barrel to be set at any angle to the horizon. On the outside of the barrel *a* is cut, or applied, a rifling proportioned to the kind of bomb to be thrown. This rifling starts from the butt end and develops helically right to the muzzle of the barrel and, as in ordinary guns, has the special object of imparting a spinning motion to the projectile surrounding the barrel, but helps also to cool the barrel itself.

The internal rifling is formed by helical cavities *e* cut in the shape of turbine blades which have the object of helping the projectile to spin by utilizing the gases developed by the explosion of the reaction charge and coming out from the inclined holes drilled in tube *d* fixed in the central part of projectile *f*, said reaction charge taking fire immediately after the explosion of the propelling charge.

The propelling charge *x* is placed within the firing barrel *a* surrounding the contracted portion *i* of the tube *d*, this charge is confined at its ends by the enlargement of tube *d*, and breech plug *b* and is ignited by means of firing device *l* of any known type.

Said reaction charge is ignited by the gases developed after ignition of the propelling charge which enter through the restricted portion *i* of the inner tube *d* of the bomb. Thus the reaction charge is ignited immediately after the propelling charge and acts from that time until its exhaustion to maintain the projectile at more or less the initial velocity.

A different form of execution of above

said parts, shown in Fig. 7; besides utilizing the pressure of the propelling charge on the tube containing the reaction charge utilizes the action of the momentum of the gases developed by the explosion on the front bottom of the bomb or torpedo, the firing barrel having always, the function of imparting the first impulse and spin and of creating the first part of the trajectory of the bomb and the reaction charge maintaining the function of helping to obtain said spin and to increase the projectiles throw.

In order to better utilize the energy of the propelling charge without too much fatiguing the tube containing the reaction charge the barrels bore is surrounded by a number of longitudinal straight or helicoidal holes a^1 of proper section, somewhat choke-bored at the muzzle, so that the gases developed by the explosion of the propelling charge contained in chamber u may be guided towards the front bottom of the projectile f in which are cut recesses provided with a certain number of ribs k . Said outflowing gases on impinging against the bombs bottom and on being deflected a certain angle against above said ribs, yield their momentum and give the greatest impulse at the same time they start and help the spinning of the projectile, acting in a similar way as steam does against the blading of a turbine.

The gases having spent their energy against the front bottom and ribs of the projectile exhausts into the atmosphere through holes j . The above described contrivance is reduced to its simplest form and essential parts for in and design may vary within the limit of the present specification and appended claims.

Another characteristic feature of the apparatus is the firing device of the propelling charge, which consists in applying any breech-loading ordinary or magazine rifle-block l of whatsoever type: this will offer besides the advantages of low cost and easy replacement, that of very quick firing permitted by such mechanisms; once the magazine of said breech-loading block is filled with proper blank cartridges there remains but to insert the complete projectile with its propelling charge on the firing barrel, cock the firing pin and fire as with ordinary rifles.

The carriage or frame is built up with two simple angular plates m properly riveted to a sheet base plate through angle irons. Said base plate is pivoted in its centre on a pipe z going through two other plates $n-o$, the lower of which o can be properly bolted on a wooden platform or frame p so as to be placed either on the ground or on a carriage. Said lower plate carries on its front end a short pipe q and has an oblong opening r cut out in

its centre in such a way that the pivot z may move somewhat back under the recoil after firing. The braking action for the recoil and the retrieving motion can be obtained by strong india rubber rings or bands s coiled several times round pivots q and z or by any similar contrivance.

The other plate n which is rigid with plates m and can only move parallel to the base-plate o , is guided by two lateral slides t and may be engaged or disengaged at will so as to allow any kind of horizontal shift.

The vertical displacements can be obtained through the pinion v meshing with the toothed sector w fixed to the butt end of the barrel.

Having now particularly described and ascertained the nature of my said invention and in what manner the same is to be performed, I declare that what I claim is:

1. A bombing apparatus comprising a firing barrel, a propelling charge in the barrel, a bomb mounted on the barrel, a tube in the bomb, and an additional propelling charge in the tube which is adapted to act upon the bomb after the initial action of the first propelling charge.

2. A bombing apparatus comprising a firing barrel, a propelling charge in the barrel, external rifling on the barrel, a bomb mounted on the barrel, a tube in the bomb, means on the bomb for engaging with the rifling on the firing barrel, and an additional propelling charge in the tube which is adapted to act upon the bomb after the initial action of the first propelling charge.

3. A bombing apparatus comprising a firing barrel, a propelling charge in the barrel, external rifling on the barrel, internal rifling in the barrel, a bomb mounted on the barrel, means on the bomb engaging the external rifling on the firing barrel, a tube in the bomb, and an additional propelling charge in the tube which is adapted to act upon the bomb after the initial action of the first propelling charge, the gases from said additional propelling charge reacting against the internal rifling of the firing barrel.

4. A bombing apparatus as recited in claim 3, together with a carriage for the firing barrel, a pivot on which the carriage is mounted, a base plate provided with a slot in which is inserted the said pivot of the carriage, a fixed standard on the base plate, and elastic means connecting the fixed standard with the said pivot so as to compensate for the recoil of the apparatus.

5. A bombing apparatus comprising a firing barrel, a propelling charge in the barrel, external rifling on the barrel, a series of grooves in the bore of the barrel choke-bored at their inner end which communicates with the portion of the firing barrel in which is located the propelling charge, a bomb

mounted on the barrel and provided with apertures through which the gases formed during the combustion of the propelling charge may be exhausted into the atmosphere 5 after they pass through the said series of grooves in the bore of the barrel and react upon the bomb, means on the bomb engaging the external rifling on the barrel so as to impart a spinning motion to the bomb, a 10 tube in the bomb, and an additional propelling charge in the tube which is adapted to

act upon the bomb after the initial action of the first propelling charge.

6. A bombing apparatus as recited in claim 5 in which the bomb is provided with ribs at 15 the points of contact of the gases from the first propelling charge issuing from the said series of grooves in the bore of the firing barrel.

Signed this 27th day of April, 1927.

GIUSEPPE MADASCHI.
